UNITED STATES PATENT OFFICE.

JAMES C. GARNER, OF HOUSTON, TEXAS, ASSIGNOR, BY MESNE ASSIGNMENTS, TO THE GARNER GIN COMPANY, INC., OF HOUSTON, TEXAS, A CORPORATION OF TEXAS.

PNEUMATIC DISK GIN.

1,406,635.

Specification of Letters Patent. Patented Feb. 14, 1922.

Application filed April 4, 1919, Serial No. 287,644. Renewed July 5, 1921. Serial No. 482,560.

To all whom it may concern:

Be it known that JAMES C. GARNER, a citizen of the United States, residing at Houston, in the county of Harris and State of Texas, has invented certain new and useful Improvements in a Pneumatic Disk Gin, of which the following is a specification.

This invention relates to new and useful improvements in a pneumatic disk gin.

The object of the invention is to provide a device of the character described which has been particularly designed for ginning fibrous material, such as seed cotton.

Another object of the invention is to provide a gin of the character described, embodying stripper disks, arranged to co-act with stripper bars, or blades, the cotton being held by pneumatic suction against said disks, and by them carried into contact with the blades, whereby the lint is stripped from the seed, preparatory to delivery to a condenser (not shown).

Another feature of the invention resides in the provision of means for receiving the lint cotton from the disks and delivering the same to the delivery flue for conveyance to said condenser.

A still further feature resides in the provision of suitable air tubes, or flues by means of which pneumatic suction is created for holding the seed cotton against the stripper disks and for conveying the lint cotton from the gin when it has been stripped from the seed.

With the above and other objects in view, the invention has particular relation to certain novel features of construction, operation and arrangement of parts, an example of which is given in this specification and illustrated in the accompanying drawings, wherein:

Figure 1 shows a front view of the device, Figure 2 shows a sectional side view taken on the line 2—2 of Figure 1,

Figure 3 is a fragmentary front elevation,

Figure 4 is a sectional view taken on the line 4—4 of Figure 3,

Figure 5 is a transverse sectional view showing a stripper blade in its relation to

the co-acting disk, and also showing the mechanism actuating the blade.

Figure 6 shows a fragmentary plan view of the blade bar,

Figure 7 shows a transverse sectional view of the blade support,

Figure 8 shows a transverse sectional view thereof, showing the stripper blade mounted thereon,

Figure 9 shows a transverse sectional view thereof showing the blade, and clamp cap secured thereto,

Figure 10 is a detail of the hinge connection, whereby the arms, carrying the blade support, are connected to the framework,

Figure 11 shows a fragmentary sectional view of the inlet end of the delivery chute.

Referring now more particularly to the drawings, wherein like numerals of reference designate similar parts in each of the figures

the numeral 1 refers to the framework, which has the supporting legs 2, 3 and 4. The framework 1 has the aligned bearings 5, 6 and 7, in which the disk shaft 8 rotates, and fixed upon this shaft, and spaced apart, are the perforated stripper disks 9. Supported by the framework and arranged behind said disks are the suction pipe 10, and the conveyer pipe 11, the latter being arranged underneath the former. The section 10' of the suction pipe 10 has a swiveling connection with the adjacent sections, permitting said section to turn, and said section is formed with a plurality of suction flues 12, whose free ends are arcuate in general contour to fit between the corresponding disks 9 and rest upon the shaft 8. The section 11' of the conveyor pipe is likewise connected to the adjacent sections with swivelling connections to permit the turning of said section 11', and this section is formed with conveyor chutes 13, whose free ends normally project between the corresponding disks 9. It is to be observed that the flues 12 are arranged to alternate with the chutes 13, the flues 12 resting between the alternate spaces between the disks 9 and the chutes 13 projecting into the other spaces.

Figure 1 shows a front view of the device, Figure 2 shows a sectional side view taken on the line 2—2 of Figure 1, Figure 3 is a fragmentary front elevation, Figure 4 is a sectional view taken on the line 4—4 of Figure 3, Figure 5 is a transverse sectional view showing a stripper blade in its relation to the co-acting disk, and also showing the mechanism actuating the blade. Figure 6 shows a fragmentary plan view of the blade bar, Figure 7 shows a transverse sectional view of the blade support, Figure 8 shows a transverse sectional view thereof, showing the stripper blade mounted thereon, Figure 9 shows a transverse sectional view thereof showing the blade, and clamp cap secured thereto, Figure 10 is a detail of the hinge connection, whereby the arms, carrying the blade support, are connected to the framework, Figure 11 shows a fragmentary sectional view of the inlet end of the delivery chute. The section 10' of the suction pipe 10 has a swiveling connection with the adjacent sections, permitting said section to turn, and said section is formed with a plurality of suction flues 12, whose free ends are arcuate in general contour to fit between the corresponding disks 9 and rest upon the shaft 8. The section 11' of the conveyor pipe is likewise connected to the adjacent sections with swiveling connections to permit the turning of said section 11', and this section is formed with conveyor chutes 13, whose free ends normally project between the corresponding disks 9. It is to be observed that the flues 12 are arranged to alternate with the chutes 13, the flues 12 resting between the alternate spaces between the disks 9 and the chutes 13 projecting into the other spaces. Provision is made for creating a suction of air through the suc-

tion and conveyor pipes 10 and 11 by any suitable current generator (not shown). In actual use, these pipes will usually be united into a common pipe with a suction 5 fan, of conventional form, located therein.

The arcuate free ends of the flues 12 are open at each side, and the air suction there-through draws the air through the perforations of the disks 9 on each side.

10 Seed cotton is delivered to the transverse apron 14, arranged above and behind the disks, and is delivered from it through the spaced hoppers 15 to the disks. These hoppers are arranged alternately, with respect 15 to the suction flues 12, and oppositely, with respect to the chutes 13 and through them the seed cotton is fed into the disk spaces between the suction flues 12. The shaft 8 has a pulley 16 fixed thereon, through which 20 rotation is imparted to said shaft, and the disks, carried thereby, in the direction indicated by the arrows, in Figures 4 and 5.

The cotton is held against the sides of the disks, between which it is fed, by the suction 25 of the air, through the perforations thereof, and is carried by said disks against the blades 17, located between said disks. These blades project between said disks and their edges fit closely against the inner sides of 30 the adjacent disks. Said sides of said disks are provided with radiating arcuate grooves 18, which engage with the cotton and tend to force it outwardly to distribute it along the full length of the blades to provide for 35 the maximum stripping effect thereof. The blades 17 are supported by a transverse bar 19, whose ends are formed with depending arms 20, 20, whose lower ends are pivoted to the front legs 3 and 4. The upper ends 40 of these arms have aligned circular openings 21, 21, through which the shaft 22 extends. This shaft is mounted in the aligned bearings 23, 24 and 25, carried by the framework and has eccentrics 26 carried thereby and 45 located in the openings 21. The shaft 22 has a pulley 27 fixed thereon in alignment with a pulley 28, fixed on the shaft 8, and a belt 29 operates over said pulleys and transmits rotation from the latter to the former, 50 and the shaft 22 is thereby rotated. The rotation of the shaft 22 operates, through the eccentrics 26, to oscillate the arms 20, 20 and the blades 17, carried thereby, the oscillation of the blades rendering them more 55 efficient in stripping the lint from the seed and preventing the congestion of the cotton against them.

The blades rest upon the supporting fingers 30, spaced apart and formed integrally 60 with the bar 19 and are clamped thereon by means of caps 31, triangular in cross section, and secured in place by means of bolts 32, 32, which pass through said caps and blades and are tapped into the fingers underneath. As the edges of the blades become

worn, causing too much clearance, it becomes necessary to adjust them and to provide for this adjustment the blades are formed of lengthwise sections. The sections have the inside opposing notches 33, 33 forming 70 openings through which the bolts 32, 32 pass and said notches are formed with the front sloping sides 34, 34, which diverge. Opposite the outer ends of the blades the bar 19 has the upstanding ears 35, through which the set bolts 36 are threaded and the inner ends of these bolts rest against the plates 38, which in turn rest against the outer ends of the corresponding blades. When the edges of the blades wear, causing too much 80 clearance between them and the disks, the bolts 32, 32 may be loosened and the set bolts screwed against the plates 38, which will force the blades inwardly, and the sloping sides 34 of the openings 33, acting 85 against the bolts 32 will cause the blade sections to spread apart until the desired clearance is attained and the bolts 32, 32 then tightened, clamping said sections in fixed 90 position.

As above stated, the cotton fed between the stripper disks is held by air suction against the sides of the disks and carried by them against the edges of the blades, by which the seed are arrested and the lint 95 passes on between the disks and the blade edges, the lint being stripped from the seed by the combined action of the disks and oscillating blades. During this operation, the seed work out along the sides of the caps 100 31 in the troughs formed by the sloping sides of said caps and the adjacent disks and when freed of the lint they are no longer subject to the air suction, and pass over the blade bar 19 into a suitable receptacle 105 provided for them.

The free ends of the delivery chutes 13 are provided with side slots 39, 39 through which the lint enters into said chutes. These inlets, as is obvious, are restricted, to increase the force of the suction to insure the entrance of the lint therein. After the lint is carried by the disks past the ends of the suction flues 12 it passes beyond the range of the suction through the disk perforations and comes within range of the suction 110 through the chutes 13 and is free to enter into said chutes through which it is carried into the conveyor pipe, and any lint which may be drawn through the perforations of the disks passes through the flues 12 into the suction pipe, and said lint is then conveyed by said pipes, by suction, to the condenser.

As stated, the sections 10' and 11' are 125 rotatable so that the flues 12 and chutes 13 may be withdrawn from between the disks 9, as shown in dotted lines, in Figure 4, thus making provision for gaining access to the disks for repairing or cleaning the same. 130

What I claim is:—

1. A cotton gin including a plurality of perforated disks fixed in spaced relation to each other, suction flues projecting into the alternate spaces between the disks, receiving chutes which project into the other spaces, and stripping blades arranged to extend into the last mentioned spaces above said chutes. 60
2. A gin for seed cotton including a plurality of perforated disks, fixed in spaced relation to each other, means for rotating said disks, a plurality of suction flues, a plurality of delivery chutes, said flues and chutes being arranged alternatively and projecting 70 into the corresponding spaces between the disks, and stripper blades arranged in the spaces into which said chutes project and co-acting with disks to strip the lint from the seed. 75
- 20 3. A gin for seed cotton including a plurality of perforated disks, fixed in spaced relation, means for rotating said disks, a plurality of suction flues, a plurality of delivery chutes, said flues and chutes being arranged alternatively and projecting into opposite spaces between the disks, and oscillating blades which project into the chute spaces. 85
4. A gin for seed cotton including a plurality of perforated disks fixed in spaced relation, means for rotating the same, a suction pipe, a conveyor pipe, a plurality of suction flues connected to the suction pipe, a plurality of suction chutes connected to the conveyor pipe, said flues and chutes being alternatively arranged and their free ends projecting into the opposing spaces between the disks, hoppers discharging seed cotton into the chute spaces, and stripper blades 90 which project into the spaces between the hoppers and chutes. 95
5. A device of the character described including a plurality of perforated disks spaced apart and fixed in their relation to each other, means for rotating the disks, a suction pipe, a suction flue connected to said pipe and projecting into the space between two of said disks, said flue having lateral openings through which the air is drawn through the perforations of the disks, a conductor pipe, chutes connected thereto, arranged on opposite sides of the flue and projecting into the corresponding spaces between the disks, hoppers arranged to deliver seed cotton into said last mentioned spaces which is held against the disks on each side by the air suction through the 100
- 105 disk perforations and oscillating blades projecting into said last mentioned spaces against which said cotton is carried by said disks, said blades arresting the seed and the disks co-acting with said blades to strip the lint cotton from the seed and deliver the same to said chutes. 110
6. In a device of the character described a plurality of perforated stripper disks, spaced apart and fixed in relation to each other, suction flues, and conveyor chutes alternatively arranged and projecting into the corresponding spaces between the disks, 70 stripper blades arranged in the spaces into which the chutes project, which cooperate with the disks to strip the lint of seed cotton, delivered into said spaces, from the seed thereof, said flues being arranged to receive 75 said lint and to convey the same from said spaces. 80
7. In a device of the character described a plurality of perforated stripper disks, fixed in spaced relation, means for rotating the same, suction flues, and conveyor chutes alternatively arranged and projecting into the corresponding spaces between the disks, hoppers arranged to discharge seed cotton into the flue spaces, stripper blades projecting 85 into said last mentioned spaces between the hoppers and chutes, said disks cooperating with the blades to strip the lint cotton from the seed preparatory to its delivery to said chutes. 90
8. In a device of the character described a plurality of perforated stripper disks, a shaft upon which said disks are fixed in spaced relation, means for rotating the shaft, a suction pipe, a conductor pipe, a plurality of flues fixed to the suction pipe, a plurality of chutes entering the conductor pipe, said flues and chutes being arranged alternatively with respect to each other and their free ends projecting into the corresponding spaces between the disks, a plurality of hoppers arranged to discharge seed cotton into the spaces into which said chutes project, and oscillating stripper blades arranged in said last mentioned spaces between said hoppers and chutes. 100
- 105 In testimony whereof, he has signed his name to this specification, in the presence of two subscribing witnesses.

JAMES C. GARNER.
